UNITED STATES PATENT OFFICE

138,785

DESIGN FOR A CHILD'S VEHICLE

Alma Streater, Spring Park, Minn.

Application June 9, 1944, Serial No. 113,935

Term of patent 14 years

(Cl. D34—15)

To all whom it may concern:

Be it known that I, Alma Streater, a citizen of the United States and residing in the city of Spring Park, county of Hennepin, State of Minnesota, have invented a new, original, and ornamental Design for a Child's Vehicle, of which the following is a specification, reference being had to the accompanying drawing, forming a part thereof, wherein,

I claim:

The ornamental design for a child's vehicle, as shown.

ALMA STREATER.
